CLAIM

The ornamental design for a fishing reel drag, as shown and described.

DESCRIPTION

FIG. 1 is a first perspective view of a fishing reel drag in accordance with a first embodiment.

FIG. 2 is a second perspective view of the fishing reel drag illustrated in FIG. 1.

FIG. 3 is a first side elevational view of the fishing drag illustrated in FIG. 1.

FIG. 4 is a second side elevational view of the fishing reel drag illustrated in FIG. 1.

FIG. 5 is a top plan view of the fishing reel drag illustrated in FIG. 1.

FIG. 6 is a bottom plan view of the fishing reel drag illustrated in FIG. 1.

FIG. 7 is a first edge elevational view of the fishing reel drag illustrated in FIG. 1.

FIG. 8 is a second edge elevational view of the fishing reel drag illustrated in FIG. 1.

FIG. 9 is an enlarged partial perspective view of the fishing drag.

FIG. 10 is an enlarged partial perspective view of the fishing reel drag.

FIG. 11 is a partial perspective view, similar to FIG. 9, of a portion of the fishing reel drag in accordance with a second embodiment; and,

FIG. 12 is an enlarged partial perspective view the fishing reel drag in accordance with the second embodiment illustrated in FIG. 11.

In the drawings, the broken line illustration of the environmental structure (the remaining structure of the fishing reel part) in the drawings is not part of the claimed design. In other words, the broken lines in the drawings depict portions of the fishing reel drag and environmental structure that form no part of the claimed design.

(Continued)

The dash-dot-dash broken lines= In in FIGS. 11 and 12 illustrate the boundary of the enlarged drawing views and form no part of the claimed design. In other words, in FIGS. 11 and 12, it should be understood that the claimed design extends to the boundary but does not include the boundaries shown in broken lines (dash-dot-dash).
